[57] CLAIM

The ornamental design for a pair of athletic shoes, as shown and described.

DESCRIPTION

FIG. 1 is a view of the inner sides of a pair of athletic shoes showing my new design;

FIG. 2 is a perspective view of the right shoe thereof;

FIG. 3 is a top view of the right shoe thereof;

FIG. 4 is a view of the inner side of the right shoe thereof;

FIG. 5 is a view of the outer side of the right shoe thereof;

FIG. 6 is a front view of the right shoe thereof;

FIG. 7 is a back view of the right shoe thereof;

FIG. 8 is a perspective view of the left shoe thereof;

FIG. 9 is a top view of the left shoe thereof;

FIG. 10 is a view of the inner side of the left shoe thereof;

FIG. 11 is a view of the outer side of the left shoe thereof;

FIG. 12 is a front view of the left shoe thereof; and,

FIG. 13 is a back view of the left shoe thereof.

The surfaces of the article not shown in the drawing or described in the specification form no part of the claimed design.
